UNITED STATES PATENT OFFICE.

CHARLES F. MEILINK, OF TOLEDO, OHIO.

BOLT MECHANISM.

Application filed August 10, 1923. Serial No. 656,755.

This invention relates to bolt throwing, controlling, and mounting mechanisms.

This invention has utility when incorporated in connection with closures of the 5 single and double door type for vaults and safes.

Referring to the drawings:-

Fig. 1 is a front view of a safe, having an embodiment of the invention incorporated 10 therewith;

Fig. 2 is a fragmentary view, on an enlarged scale, of portions of the doors of Fig. 1, with the front plate of the doors removed;

Fig. 3 is a fragmentary view of the bolt 15 throw devices of the doors, with the back plates removed, looking at the devices from the rear or inside of the safe;

Fig. 4 is a fragmentary, horizontal section on the line IV—IV, Fig. 1;

Fig. 5 is a still further enlarged fragmentary section of the bolt lock side of the device of Fig. 4; and Fig. 6 is a fragmentary section of the line VI—VI, Fig. 2.

The safe as shown is provided with an 25 outer wall 1 and inner wall 2 spaced therefrom. Between these inner and outer walls 1 and 2 there is connecting frame 3 for a front opening. Along one side of this front opening, there is a pair of hinges 4 mounting a door 5. Along the opposite edge of this frame 3 of the front opening, there is a second pair of hinges 6 mounting a companion door 7 with the door 5. The door 5 is shown as having a frame 8 which is connected on the front by a plate 9 and on the back by a plate 10, thereby forming a metal housed door section. The second or companion door 7 is shown as comprising a frame 11, closed at the front by a plate 12 and at the rear by a plate 13. The double 30 wall of the safe housing 1, 2, as well as the double wall double door structure, have as filler between the double walls thereof, insulation material 14. The frame 3 between the 35 walls 1 and 2 of the safe is of such form as to interfit with the frames 8 and 11 of the doors 5 and 7, and furthermore these doors 5 and 7 have an interfitting relation at their central portion.

On the upper free end portion of the frame 8 of the door 5, there is shown a disc 15 as a 40 guide for a bolt 16, in its throw outward through opening 17 into frame 3. Remote 45 therefrom, in the lower part of this door 5,

in the frame 8, is shown a disc 18 as a guide 55 for a bolt 19 to be thrust downward as the bolt 16 is thrust upward. This bolt 19 is thrust downward to enter opening 20 of the door frame 3 between the inner and outer walls 2, 1. From the bolt 16 extends downward, a link 21 loosely connected for slight play as to bolt 16 and for slight play as to the crank rocker 22. The opposite arm of this rocker 22 is connected by link 23 with the lower bolt 19 for slight looseness in 60 connection. The freedom or looseness between the elements of this linkage and crank construction insures ease of operation and facilitates assembly, with avoidance of binding between the bolt series. Frangible pin or 65 screw 24 connects this rockable member 22 with D-plate or washer 25 which is held by nut 26 in locked or seated position with spindle 27 extending through the front plate 9 of the door 5 to carry handle 28. This 70 rocker spindle 27 in its extent from the rocker member 22 to the front door plate passes through tube 29 which extends back to engage annular flange carrying plate or member 30 as a shield for the bolt throw 75 mechanisms and furthermore to keep the insulation filler therefrom.

In this double door safe structure, a guard 80 is provided insuring that the bolt must be thrown into locked position in door 5 before the bolts may be thrown in door 7, which door 7 carries the lock. To this end there is provided a pin or connection 85 31 operable with and carried from an extension of an arm of the rocker 22 which connection or pin 31 is of a length to extend into cam slot 32 of sheet metal guard 33 having slots 34 guiding this plate 33 on pins 35 carried by the member 30. This 90 guard plate 33 has concavo-convex bolt portion 36 extending through opening 37 as a guide way from the member 30 and through the frame 8. The slot 32 is so designed as to the action of the rocker 22 that in the throwing of the bolt into locking or holding 95 position by thrusting the links 21, 23, away from the rocker 22, it causes the bolt portion 36 of the guard member 33 to be withdrawn from locking position as to the guide way 37 so that this portion 36 is not in flush 100 position with the outer end of such guide way. When the handle member 28 is rocked 105 to throw the rocker member 22 so that the

links 21, 23, withdraw their respective bolts 16, 19, this guide plate 33 instead of being withdrawn is thrust outward as the pin 31 rides into the slot 32 to urge this member 33 so that the bolt portion 36 thereof is flush with the outer end of the guide 37. The position of the rocker 22 in Figs. 2 and 3 is in the withdrawn position of the bolts and accordingly in the thrown position of the 10 guard 33. An adjustable stop is provided for the guard plate. To this end, this guard plate 33 is shown as having a lateral offset portion or extension 38 (Fig. 3) which in reciprocation of the guide plate or arm 33 15 abuts adjustable stop or bolt 39 mounted in clip 40 to limit the withdrawing of this guide plate while the thrown position of the guide plate may be limited by the pin 31. This bolt 39 is maintained in locked position by 20 lock nuts 42.

The second or lock carrying door is shown in Fig. 2 as having its frame 11 provided with a ferrule 43 as a guide for bolt 44 which travels through opening 45 into the 25 frame 8 on the door 5, upper portion, while below the door 7 is shown as having a ferrule 46 as a guide for bolt 47 which travels into and out of opening 48 of the frame 8 of the door 5. Loosely connected with bolt 30 44 is lever 49 mounted on fulcrum 50 and this lever extends downwardly while a lever 51 from the bolt 47 upwardly extends having fulcrum 52. These levers 49, 51, extend to rocker member 53. This rocker member 53 is shown as having frangible pin or screw 24 connecting such rocker 53 with plate 25 locked by nut 26.

This plate 25 has key connection with spindle 27 extending through the front plate 40 12 of the door 7. Mounted on the spindle 27 is control handle 54'. This spindle 27 is surrounded by tube 29.

This rocker 53 is shown as having an arm 54 remote from the arm connected with the 45 levers 49 and 51. This arm has pin 55 engaging bolt 56 to reciprocate this bolt 56 by way of guide 57 into opening 37 of companion door 5 of this double door structure which operates only as the guide plate 50 33 has its bolt 36 withdrawn. Accordingly it is not possible to rock the handle 54' into bolt locking thrown position as to the door 7 until the handle 28 of this door 5 has thrown the bolt in door 5 into locking position.

When this dual operation of throwing the bolt first in the door 5 and then in the door 60 7 occurs, locking of the several bolts of the bolt control mechanism occurs. To this end the rocker 53 is shown as having an arm 58 having an offset portion 59 with an opening 60 therethrough. This opening 60 may have bolt 61 from lock 62 enter and thus hold the arm 58 together with the rocker 53 65 in locked position. By thus holding the

rocker 53 in locked position there is an effective holding of the bolts in the door 7 as held by the levers 49 and 51 and there is a resultant holding of the levers in the door 5 as thrown by the links 21, 23, for the 70 rocker 22 may not be thrown into bolt withdrawing position as the bolt 56 precludes such shifting of the guard 33.

This lock 62 has extending therefrom a spindle 63 having index plate 64 in front of the door 7 as a tumbler throwing or control device for this lock 62. This spindle 63 is surrounded by spindle tube 65 having front portion held by nut 66 within or back of the index plate 64. This spindle tube 65 engages lock and bolt throw holding annular flange carrying plate or member 68 which has spot-weld connected flange 69 anchoring the member 68 with the door frame 11 on the door 7.

Besides the utility of the looseness of the different rockers and the different bolts for acting independently to avoid any binding being transmitted from one bolt to another, there is utility in the holding of this structure in locked position against attack say by knocking off the lock spindle, or attempt at forcing the structure by driving the lock spindle inward. Any shifting of the lock 62 brings about a binding of the bolt 61 in opening 60. Furthermore any attempt to drill the front plate 12 and shift the rocker plate 58 also brings about a binding action. Accordingly this structure is one doubly safe-guarded in the holding value of this lock as against exterior attack. The looseness of the bolt structure permits freedom of operation at all times when the lock is released. This looseness is only sufficient to permit ready throwing of the bolts.

For more fully isolating the bolt mechanism from the filler and thereby maintaining the structure in condition for easy operation at all times, the bolts may be housed as more clearly shown in Fig. 6. The door frame 3 as to its openings 17, 20, is shown as having at such openings flanges 70 of disc form about said openings to carry and register with said respective pockets 71 about which extends the insulation filler 14. The 110 discs 15, 18, are shown as two parts. Each has extending therefrom sections 72, 73, united to form a tubular pocket having on the outer sides thereof and parallel to the disc portions, ribs 74 providing on the inner side of the tube lubricant carrying pockets 75 in which may be placed a hard oil or graphite. There is thus provided a simple construction for maintenance of freedom of movement of the bolts 16, 19, as actuated by 115 respective links 21, 23, connected through the slots 76, in the pockets 72, 73, as housing the bolts from the insulation 14.

This detail of bolt construction is one materially contributing to ease of operation in 130

bolt throwing into and out of locking position even though there be long lapses of time between the operations.

What is claimed and it is desired to secure by Letters Patent is:—

1. A double walled door provided with a sheet metal frame connection between said walls having a bolt way therethrough, throwing means for the bolt, a lock for the throwing means, and a support for the lock having a flange parallel with the inner wall of the frame and there anchored to said frame.

2. A double walled door provided with a frame connection between said walls having a bolt way therethrough, throwing means for the bolt, a lock for the throwing means, a spindle for the lock, a tube for the spindle, and a support for the lock to which the tube is connected, said support having a flange parallel to the inner wall of the frame, extending away from the bolt and there anchored to said frame independently of said tube.

3. A door provided with a frame, inner and outer walls carried by the frame, a lock, and a sheet metal member supporting the lock between the walls and having a flanged side of the member extending to the frame and there anchored parallel with an inner side wall of the frame.

4. A door provided with a frame having an opening, inner and outer walls carried by the frame, bolts carried by the door, bolt throw mechanism for the door carried bolts, an arm slidably by the mechanism into intercepting position at said opening as the mechanism operates the bolt into door holding position, and a bolt carried independently of the door operable through said opening for further locking the door.

5. A door provided with a frame having an opening, inner and outer walls carried by the frame, bolts carried by the door, bolt throw mechanism for the door carried bolts, a slidably arm operable by the mechanism out of intercepting the opening as the door carried bolts are operated by the mechanism into door holding position, a member for the lock, and an additional bolt carried independently of said door and registering with said arm opening when the door is closed and precluded from entering the opening and binding therewith in any shifting of the member.

6. A door having bolt discharge and bolt receiving openings, a bolt for the bolt discharge opening, a guard for the bolt receiving opening, and bolt throw mechanism for retracting the bolt as the guard is shifted to intercepting position at the bolt receiving opening.

7. A support, bolt throw mechanism mounted by the support, an arm shiftable by the mechanism, said arm having an ex-

tension, said support having an opening toward and from which said extension is movable with the arm, an adjustable stop for limiting the movement of said extension, and a lock provided with a bolt movable to engage said openings as said extension is clear of said opening.

8. A double door bolt control mechanism for a pair of doors, rocker members mounted by the doors and provided with arms, one of said arms having bolt travel intercepting means, an adjustable stop for said intercepting means carried by one of the doors, and a bolt reciprocable toward and from said intercepting means.

9. A door frame, a first door hinged to one side of said frame and having openings, a slideable guard carried by the first door for one of said openings, a bolt for another of said openings, a second door oppositely hinged to said frame and having bolt openings, bolts carried by the second door, and bolt control mechanism carried by each door, the guard of the first door being shiftable by the mechanism of the first door to be operative in closed position of the doors for precluding shifting of the bolts of the second door into door holding position except as the bolt control mechanism of the first door is thrown into door holding position as to the frame.

10. A double door bolt control mechanism embodying a pair of rocker members provided with arms, one of said arms having an opening, a lock provided with a bolt in said arm opening, and additional means coacting between the rocker members precluding shifting of one when the other is held by said lock bolt.

11. A double door bolt control mechanism embodying a pair of rocker members provided with arms, one of said arms having an opening, a lock provided with a bolt in said arm opening, and additional aligned means coacting between the rocker members precluding shifting of one when the other is held by said lock bolt.

12. A double door bolt control mechanism embodying a pair of rocker members, a pair of opposing aligned reciprocable elements shiftable respectively by said rocker members, one of said elements being reciprocable by bolt throw as to one door before there may be bolt throw in the other door.

13. A double door bolt control mechanism embodying a pair of rocker members, a first element withdrawn by shifting one member into bolt throw position, and an aligned second element then having its way cleared for throwing by rocking of the other member.

14. A double door bolt control mechanism embodying a pair of rocker members, a first element withdrawn by shifting one member into bolt throw position, an aligned sec-

- ond element then having its way cleared for throwing by rocking of the other member, and an adjustable stop for one direction of travel of one of the elements.
- 5 15. A double door bolt control mechanism embodying a pair of rocker members, and means precluding shifting of one rocker member when the other is held, said means including an element provided with carrying and actuating slots, and pins coacting with said slots.
- 10 16. A double door bolt control mechanism embodying a pair of rocker members, and means precluding shifting of one rocker member when the other is held, said other rocker member having a pin, said means including an element provided with an actuating way eccentric of said other rocker member and coacting with said pin.
- 15 17. A safe housing provided with an opening and seat means adjacent said opening, a closure for the opening, a bolt carried by the closure, a shaft provided with a crank, and a lever loosely connected to the crank and the bolts and a fixed fulcrum for the lever whereby shaft rotation may be communicated through the lever for throwing and withdrawing the bolts as to the closure and seat means.
- 20 18. A double wall safe housing provided with an opening, a door jamb frame at said opening connecting said double walls, there being a bolt hole in the frame, there being a chamber in the frame and between said double walls, and a pocket connected at the bolt hole to be there sustained by said wall to protrude into said chamber.
- 25 19. A double wall safe door, a bolt carried thereby, there being a hole in the door through which the bolt may be projected, there being a chamber between the walls of the door, and a ribbed bolt-lubricating pocket at the hole to isolate the bolt from the chamber.
- 30 20. A double wall safe door, a bolt carried thereby, there being a hole in the door through which the bolt may be projected, there being a chamber between the walls of the door, and a self lubricating pocket at the hole to isolate the bolt from the chamber.
- 35 21. A double wall safe door, a bolt carried thereby, there being a hole in the door through which the bolt may be projected, there being a chamber between the walls of the door, and a pocket at the hole to be there sustained by the door wall at said hole to isolate the bolt from the chamber, said pocket having a flange about the hole on the side of the hole from which the pocket extends, said flange anchoring said pocket with the door at said hole.

In witness whereof I affix my signature.

CHARLES F. MEILINK.
